RAFT HOLDING AND RELEASE APPARATUS

George Sipkin, Washington, D. C.

Application February 16, 1949, Serial No. 76,744

17 Claims. (Cl. 9—33)

(Granted under the act of March 3, 1883, as
amended April 30, 1928; 370 O. G. 757)

1

This invention relates to life raft apparatus with special reference to mechanism for releasing separately and without interference each raft of a stack under conditions of submersion.

Life rafts and floats form usual equipment for ships; and stacked rafts are also employed where limitation in space or need for adequate supply of units is important. Previously, stacked rafts have been secured to ship decks through use of permanent fixtures, including turnbuckles and sliphooks, which require manipulations when there is need for release of the rafts. Obviously, such attachments do not function in case of sudden sinking of the ship; and when released manually during heavy seas the rafts will slip as a unit tending to cause piling and injury to possible users.

Automatic raft releasing apparatus has also been used involving use of float equipment, trip devices, fences and other mechanism subject to jamming on heavy ship list, or to interference between rafts at the critical time of release whereby the usefulness of the entire equipment is jeopardized.

Generally stated the present invention involves a stacking of rafts on the support, such as a ship deck, with a side edge of each raft releasably connected to the deck at the opposite side of the stack by a cable extending over the raft; so that on submersion, the rafts are released alternately from side to side of the stack without interference with each other or with the attachment or support devices.

An outstanding object of the invention is the provision of fastening apparatus for stacked rafts which will permit automatic successive release of each raft on submersion.

Another object is the provision of fastening apparatus for stacked rafts which will secure on submersion raft release at widely spaced points whereby blocking or interference between rafts is avoided.

An object also is to provide raft stack supports which permit simplification of spacer units.

Still another object is to provide raft attachment apparatus effective to secure taut and rigid placement of cables and floats on the ship deck.

A further object is to provide a deck raft stack wherein the attachment elements are all outside the stack.

An additional object is the provision of inter-raft blocks which serve the dual purpose of raft spacers and attachment holding means.

Other objects such as relate to improvement in stability and structure simplification and other

features will become apparent from consideration of the following specification relating to the annexed drawing in which:

Fig. 1 is a side sectional elevation of a submerged raft stack showing upper rafts at the time of release;

Fig. 2 is a detail showing the mode of attachment of the top raft of a stack;

Fig. 3 is a side elevation showing the attachment clips on the top instead of the outer side of the raft as in Fig. 1;

Fig. 4 is a sectional detail showing the clip and cable connections for the top and next adjoining raft of the showing of Fig. 3; taken on the line 4—4 thereof.

Fig. 5 is a perspective of the attachment clip and cable coupler;

Fig. 6 is a view in perspective of one of the spacing blocks.

Fig. 7 is a fragmentary detail view of a cable clamp; and

Fig. 8 is a perspective of the cable clamp.

Referring to the drawings, wherein like reference characters designate like parts throughout the several views, there is shown in Fig. 1 a stack 10 formed of rectangular, internally open rafts 11, 12, 13 and 14, rafts 11 and 12 being in normal attached position on the deck 15 or other support surface, raft 13 being on the swing to the release position at the left of the stack as viewed in the drawing, and raft 14 being in the position of release, with the cable 16 and attached clip 17 falling to the right.

The rafts may be of any desired shape, but for the purpose of this description they are formed of square beams turned into an oblong shape with an open interior section. The beams should be of suitable buoyant material such as wood or wood mixtures including cork. Preferably the edges of the beams are rounded to facilitate handling and application of the clips.

In the assembly of the stack the rafts are superposed on the deck 15 with a base supporting spacer 18 and intervening spacers 19, 20 and 21. In addition use is made of lashing units including clips 17, 22, 23 and 24 and cables 16, 25, 26 and 27 respectively connecting the clips to the eye bolts 28 and 29 fixed to the deck 15 on either side of the stack. While reference is made to single eye bolts and a single series of clips and cables on each side of the stack it is to be understood that preferably two sets of clips, lashings, and eye bolts are used, as will be explained more fully hereinafter.

The clips 17, 22, 23 and 24, which may be of

metal and which preferably are rigid in form, are U-shaped (Fig. 5) and include a bridge plate 30 and projecting side plates 31 and 32. Toward one end of the external surface of the base plate 30, is attached a staple 33 for connection to the attaching cable. In general, the clip is designed so that the side plates terminate about the mid-point of the raft beams so as to permit easy removal.

The clip cables 16, 25, 26 and 27 are preferably of flexible wire, but may be of textile rope, chain or other flexible connector having adequate tensile strength. It is desirable that the ends of the cables be secured directly to the staples 33 so that attachment or release of the cable ends may be made for each raft at the side of the stack. The cable may be threaded through the deck eye bolt and the ends attached to separate clips, the eye bolt cable section being lashed at the bolt to prevent slippage.

The spacers 19, 20 and 21 are interposed between the various rafts to serve at least two functions, namely, to provide stability to the stack and to assist in holding the clips in place. Each spacer, as 19, includes a central lengthwise extending rod 34 and two cross rods 35 attached as by spring slots 36 to the rod 34. To the ends of each of these rods are secured chocks or blocks 37, which may be wood or other resistant material. These blocks are T-shaped as shown in Fig. 6 with the long section 38 joining the transverse block head 39 with a curved area adapted to conform to the curved edge of the raft beam. The bearing sides of section 38 may be either flat as at 39 in Fig. 6 or stepped to form a surface 40 depressed below surface 41 for the purpose of engaging with and fitting over and retaining the side clip sections as illustrated in Fig. 1.

The base spacer 18 differs over the other spacers in that the bottom side of the blocks are flat to conform to the deck surface. If desired this base spacer may be fixed to the deck although it is usually sufficient to lash the stack to the deck by use of the eyebolts 28 and 29.

In both the base and inter-raft separators the dimensions are chosen so that the raft beams nest snugly with the recessed block surfaces thus preventing relative movement so long as the rafts remain in place on the block.

In setting up the stack the base spacer is placed between the pairs of eye bolts and the bottom raft placed on the blocks. Cable 25 is then secured to eye bolt 28 and to staple 33 in clip 22. Tautness may be insured by lifting the right side of the raft as shown in Fig. 1 for the tying operation thus securing the leverage of the raft on release of the same. The clip 22 rests in the ledge 40 of the base block 20' and is retained therein by the weight of the raft beam.

Spacer 19 is then placed on raft 11 so as to nest thereon and raft 12 placed on the spacer 19, clip 23 having previously been slipped in place on the raft beam. Cable 26 is then connected to eye bolt 15 and led over the right side of the raft as seen in Fig. 1 and across to the top of the left raft beam and to the staple 33 where it is secured. Spacer 20 is then placed in raft 12, and raft 13 on spacer 20 with the clips on the right beam of the raft and the cable extending over the raft top and left beam to the deck bolt 28. The stack may be completed by placing an additional raft 14 above raft 13 on spacer 21 using right side clip 17 and cable 16, and an unat-

tached top raft on a spacer (not shown) above raft 14. (See Fig. 3.)

The operation of the life rafts may now be considered under conditions of submersion. Where sudden submersion occurs due to sinking of the ship, the top raft being unattached floats freely upwards, relieving pressure on the second raft from the top which immediately pivots upward on the lower spacer blocks on the side of the stack at which the clip cable is attached to the deck. In the illustration of Fig. 1 the raft 13 is shown pivoting to the left on block 37 of spacer 20. As the raft turns on its edge a point is reached approaching vertical alignment when the cable is straight under tension and the base edge of the raft clears the block head of its spacer support. Thereupon the raft pivots on the clip attachment until the approximate position of raft 14, Fig. 1 is reached where the buoyancy of the raft serves to lift it away from the clips 17, and the cables fall to the right.

In this operation as the rafts assume a vertical edge position the spacer supported thereby slips to the side of the stack at a point involving no interference with the ascending rafts. Clearance of the spacers is aided by the side momentum acquired thereby in the pivoting movement from the top of the stack. This lateral movement of the rafts is increased also by the initial buoyant pivoting of the next lower raft which, as in the case of raft 12, Fig. 1, lifts its left edge and spacer against the turning lower edge of raft 13. Thus as regards both the spacers and cables release thereof is effected at the extreme sides of the stacks while influenced by the lateral momentum of the raft pivoting whereby clearance of the stack is assured.

The utility of the clip attachment is now apparent in that it insures release of the rafts alternately on the extreme sides of the stack under conditions of lateral outward momentum to insure complete freedom from interference between stacks, spacers and cables, and release of the rafts at spaced points so that they will not surface at precisely the same area. The U-form of the clip, moreover, is such that accidental grabbing of the same on the rafts is made impossible as might develop if a hook form were used.

It is pointed out further that the clip engagement on the raft beam need not be tight since in stack formation the adjacent upper spacer rests on the clip and holds it in position. Under storm conditions consequently the stack is stable. This stability may be assisted in the case of the top raft, which is normally unattached, by placing edge clips 40' (Fig. 2) on the top raft beam directly above the clips of the next lower raft and joining the two sets of clips by a flexible cable 41 of such length that when the top raft is in position the cable is taut. In the case of submersion the top raft pivots on the clip until free as in the case of the other rafts.

While automatic staggered release of the rafts under conditions of submersion is a prime consideration, conditions arise where it is desirable to free the rafts before submersion. Under such conditions the time element becomes important and it is desirable that there be no complex releasing devices or operations to hinder quick removal of the rafts. In the case of the lashings of Fig. 1, to remove the rafts manually without pivoting would require untying of the knot which might involve more time than may be available. To overcome this difficulty the cable end, instead

of being knotted, may be secured by the clamp 50 (Figures 7 and 8), preferably placed on top of the raft beam between the rafts so as to be normally inaccessible without removal of the top rafts.

The clamp 50 comprises a strap casing 51 of oblong shape having an end slot 52 forming a guide way for the handle 53 of a clamp lever pivoted on cross shaft 54. The lever carries an arm 55 integral with lever arm 53 but angularly related thereto so that when the cable end is threaded through the clamp casing, the staple 33, and again through the casing in reverse and the handle 53 compressed the arm 55 forces the cable sections together and locks them in place. The forcing action of the clamp tends also to increase the tautness of the cable connection between ends when positioned as shown. Preferably the handle has flaring edges 56 which project to the side of the cable where they may be readily grasped to force a quick release of the cable. Obviously, other connectors such as a slip ring hook may be employed.

Also facilitating rapid removal of the rafts is the modified arrangement of the clip attachment shown in Figures 3 and 4. In this arrangement the clips 45 are placed on the tops of the respective raft beams where they are normally held in place by the adjoining upper spacers 46. It is pointed out that the staple 33 is placed adjoining the end of base section 30 so that the staple will not interfere with the spacer in any way. As in the preferred form the top raft may be provided with clips 47 directly above the clips of the next lower raft, with cables 48 joining the clips together. On submersion this form of clip releases at a smaller angle of lift but it has the advantage of permitting removal of the clips manually without use of special release mechanism or pivoting of the rafts.

It is noteworthy that the clip attachment mechanism accords high stability of the rafts in stack as well as easy automatic release on submersion, without use of complex mechanism. It is of note further that raft blocking or interference on automatic release when submerged is practically eliminated by utilizing the lateral momentum of the pivot action and delaying release until the rafts have pivoted to alternate sides. Further it is pointed out that the lashings are accessible from the stack sides, that manual release may be readily effected, that large spacers are not essential, and that all rafts are bound together as a unit in the deck stack.

The invention herein described may be manufactured and used by or for the Government of the United States of America for governmental purposes without the payment of any royalties thereon or therefor.

It should be understood that the foregoing disclosure relates to preferred embodiments of the invention and that numerous modifications or alterations may be made therein without departing from the spirit and scope of the invention as set forth in the appended claims. For example, the spacer blocks 37 need not necessarily rest on the clips in both modifications but the clips may be placed on the raft beams adjacent the blocks thereby rendering it unnecessary to undercut the blocks 37 as shown at 40 in Fig. 6.

What is claimed is:

1. In stack holding and release equipment, a base support, a group of superposed buoyant raft members mounted in stack formation on said support, attachment elements removably secured

to each of said group members at alternate sides of said stacks for successive members, and cables connecting each of said elements to said support.

2. In stack holding and releasing equipment, 5 a base support, a group of superposed buoyant raft members mounted in stack formation on said support, U-shaped attachment elements removably secured to each of said group members successively at alternate sides of said stack, and cables connecting each of said attachment elements to the support on a side of the stack opposite each of said respective elements.

3. In stack holding and releasing equipment, 15 a base support, a group of superposed buoyant raft members mounted in stack formation on said support, attachment elements removably secured to each of said group members successively at alternate sides of said stack, and cables connecting each of said attachment elements to the support on a side of the stack opposite each of said respective elements, said cables extending from each element over the top of the adjoined raft and down the stack side opposite to the element.

25 4. In stack holding and releasing equipment, a base support, a group of superposed buoyant raft members mounted in stack formation on said support, attachment elements removably secured to each of said group members successively at opposite sides of said stack, and cables connecting each of said attachment elements to the support on a side of the stack opposite each of said respective elements.

30 5. In marine equipment, a base support, superposed buoyant members mounted in stack formation on said support including side sections, spacers positioned in said stack between the successive superposed members, attachment clips removably secured to the side section of each 40 of said members with portions of said clips interposed and held between the member and spacer, and a flexible cable extending from each clip over the top of the member to which the clip is attached to the opposite side thereof and to fixed attachment means on said support.

45 6. In marine equipment, a base support, superposed buoyant members mounted in stack formation on said support including side sections, spacers positioned in said stack between the successive superposed members, attachment clips removably secured to the side section of each of 50 said members with portions of said clips interposed and held between the member and spacer, a flexible cable extending from each clip over the top of the member to which the clip is attached to the opposite side thereof and to fixed attachment means on said support and a manually releasable latch between each of said cables and the connecting clip.

60 7. In marine equipment, a base support, superposed buoyant raft members mounted in stack formation on said support, attachment elements secured to each of said buoyant members successively at alternate sides of said stack, and cables connecting each of said attachment elements to the support on the side of the stack opposite each of said respective elements.

70 8. In stack holding and releasing equipment, a base support, a group of superposed buoyant members mounted in stack formation on said support, attachment elements removably secured to each of said group members successively at alternate sides of said stack, cables connecting each of said attachment elements to the support on a side of the stack opposite each of said

respective elements, and a manually releasable latch interposed between each of said cables and the adjoining attachment element.

9. In marine equipment, a base support, a group of superposed buoyant members mounted in stack formation on said support, attachment elements secured to each of said group of stacked members at successively opposite sides of said stack, a separate top member on said group of members, an attachment element secured to the top member at a point adjacent the element of the next underlying member, cables connecting each of said group attachment elements to the support on the side of the stack opposite each of said respective elements, and a cable connecting the element on said top member to the next inferior member element.

10. In marine equipment, a deck support, plural rafts superposed in stack formation on said support, said rafts separated from each other by interposed separating elements to provide intervening spaces therebetween; said rafts having buoyant rectangular side beams, U-shaped clips removably mounted on each raft on beams at alternate sides of the stack as taken in succession from raft to raft, and cables connecting each of said clips on one side of the stack to a fixed connector on the support on the opposite side of the stack.

11. In stack holding and releasing equipment, a base support, a group of superposed buoyant raft members mounted in stack formation on said support, attachment elements removably secured to each of said group members successively at alternate sides of said stack, cables connecting each of said attachment elements to the support on a side of the stack opposite each of said respective elements, a top buoyant member on said group of members, and means for releasably attaching said top member to said group of members.

12. In marine equipment, a base support, superposed buoyant members mounted in stack formation on said support including side sections, attachment clips removably secured to the side section of each member, a cable extending from each clip over the top of the member to which the clip is attached to the opposite side thereof and to fixed attachment means on said support, and means for spacing the buoyant members and retaining said clip thereon.

13. In marine equipment, a deck support,

plural rafts having square sectioned side beams superposed in stack formation on said support, U-clips placed on the beams of each raft on alternately opposite sides of the stack, said U-clips opening to the stack interior, and a cable joining the outer face of each of said respective U-clips to the support at a point on the opposite side of the stack from said clips.

14. In marine equipment, a deck support, plural rafts having square sectioned side beams superposed in stack formation on said support, U-clips placed on the beams of each raft on alternately opposite sides of the stack, said U-clips opening downwardly and a cable joining the upper face of each of said U-clips to the support at a point on the opposite side of the stack from said clip.

15. In apparatus for securing staggered release of rafts superposed on decks in stack formation, releasable attachment members secured to one side of each raft at successively opposite sides of the stack, and a cable connecting each of said members to a fixed point on the deck.

16. In apparatus for securing staggered release of rafts superposed on decks in stack formation, releasable attachment members secured to one side of each raft at successively opposite sides of the stack, and a cable connecting each of said members to a fixed point on the deck on the side of the stack opposite to the member.

17. Apparatus for securing vertically stacked flat rafts and spacers on a support, comprising releasable attachment devices secured to edges of alternate rafts on one side of the stack, releasable attachment devices secured to the other rafts at alternate edges on the other side of the stack, and a cable connecting each of said respective devices over the opposite edge of the raft to which said devices are attached to a point on the deck on the side of the stack opposite each of said respective devices.
